Primary Examiner — Elizabeth Albert(74) *Attorney, Agent, or Firm* — Michael Best & Friedrich LLP(57) **CLAIM**

We claim the ornamental design for a saw blade, as shown and described.

DESCRIPTION

FIG. 1 is a side view of a saw blade showing my new design. FIG. 2 is an end view of the saw blade shown in FIG. 1. FIG. 3 is a top view of the saw blade and shown in FIG. 1; and, FIG. 4 is a bottom view of the saw blade shown in FIG. 1. The elements shown in broken lines are included for the purpose of illustrating environment and form no part of the claimed design. The long and short broken lines in FIGS. 1-4 that define the bounds of the claimed design form no part thereof.
